(57) **CLAIM**

The ornamental design for a medical monitor as shown and described.

DESCRIPTION

FIG. 1 is a front perspective view of a medical monitor showing our new design.

FIG. 2 is a front view of the medical monitor of FIG. 1.

FIG. 3 is a rear view of the medical monitor of FIG. 1.

FIG. 4 is a left side view of the medical monitor of FIG. 1.

FIG. 5 is a right side view of the medical monitor of FIG. 1.

FIG. 6 is a top view of the medical monitor of FIG. 1.

FIG. 7 is a bottom view of the medical monitor of FIG. 1; and,

FIG. 8 is a perspective view of the medical monitor of FIG. 1 showing the adapter in a docked state.

The broken lines in the drawings depict portions of the medical monitor that form no part of the claimed design.

1 Claim, 8 Drawing Sheets
